[57] CLAIM

The ornamental design for a canoe caddy, as shown and described.

DESCRIPTION

FIG. 1 is a perspective view of a canoe caddy showing my new design;

FIG. 2 is a top plan view thereof;

FIG. 3 is a bottom plan view thereof;
FIG. 4 is a side elevational view thereof, the opposite side elevational view being a mirror image of that shown; and

FIG. 5 is a front elevational view thereof, the rear elevational view being a mirror image of that shown.

FIG. 1.

FIG. 2.

FIG.3.

FIG.4.

FIG. 5.
